UNITED STATES PATENT OFFICE.

HENRY LANGE, OF QUINCY, ILLINOIS.

COMBINATION RANGE.

Application filed June 10, 1925. Serial No. 36,227.

The present invention relates to cooking stoves and ranges, and more particularly to combination stoves or ranges using both fluid and solid fuel for cooking, baking and heating.

It is the primary object of the invention to provide a combination range having in addition to the usual provisions for cooking and baking with gas and heating and 10 cooking by coal, wood or other solid fuel, a built-in-gas heater which may be employed for heating the room in which the range is located.

Another object of the invention is the provision of such a combination range having a novel combination and arrangement of the gas heater with reference to the coal or solid heater and the baking oven.

A further object is the provision of a 20 novel and improved radiant gas heater intended especially for use in cooking stoves and ranges.

The invention also has among its other objects the provision of a novel assemblage of 25 the component elements of the gas heater, provision for the flow of air to and from the gas heater, and provision for the discharge of products of combustion.

With the foregoing and other objects in 30 view, which will be apparent as the description proceeds, the invention resides in the construction and arrangement of parts, as hereinafter described and claimed, it being understood that changes can be made within 35 the scope of what is claimed, without departing from the spirit of the invention.

The invention is illustrated in the accompanying drawings, wherein—

Figure 1 is a perspective view of a combination range embodying the invention.

Fig. 2 is a vertical section on the line 2—2 of Fig. 1.

Fig. 3 is a vertical section on the line 3—3 of Fig. 1, with the griddle and oven door removed.

Fig. 4 is a front view of the range, partly in section on the line 4—4 of Fig. 2, with the oven door removed.

Figs. 5 and 6 are horizontal sections taken 50 on the respective lines 5—5 and 6—6 of Fig. 2.

The cooking stove or range illustrated is of conventional form in general respects, and the embodiment of the invention as illustrated and described is to be taken as typical, 55 inasmuch as the invention may be incorpo-

rated in stoves and ranges of different styles.

The range comprises a body 10 having the baking oven 11 therein with a door 12 at the front of the range to give access to the oven, 60 and below the bottom 13 of the oven is disposed a gas burner 14 for heating the oven.

The body 10 has a space or chamber 15 above the oven in which the gas burners 16 for cooking are located, and the cooking top of the body 10 includes the griddles 17 above the chamber 15, the burners 16 being located under said griddle and being supplied with gas, as usual, by a gas supply pipe 18 through the control valves 18'. The body 10 70

has a vertical partition 19 therein between the end or side walls of the body, and dividing or separating the oven 11 and burner chamber 15 from the solid fuel and gas heaters. Said body has the horizontal partitions 20 and 20' forming the top of the oven and bottom of the chamber 15, respectively, with a top oven flue 21 between said partitions 20 and 20'.

The oven 11 has side walls or partitions 22 and 23 which are located adjacent to but spaced from the partition 19 and corresponding end or side wall of the body, respectively, to provide vertical flues 24 at the opposite sides of the oven. The back wall 25 of the oven is also spaced 85 from the back wall of the body 10, as seen in Fig. 3, to provide a rear vertical flue 26. The oven bottom 13 being spaced above the bottom of the body provides a bottom flue 27 below the oven in which the burner 14 is located, and the bottom of the body has an air inlet opening 27' below the burner 14, with a shield or guard 27'' below said opening so that the air must flow along the bottom of 90 the body before passing up through the opening 27'. The products of combustion from the burner 14 pass along the oven bottom 13, and thence upwardly through the flues 24 and 26 into the top flue 21. The back wall of the body has the outlet openings 28 and 29 communicating with the flue 21 and chamber 15, respectively, and with a flue or pipe connecting member 30 secured to the back wall of the body 10 for the connection of the stove pipe or flue that carries 105 off the products of combustion from the oven and chamber 15. It will be apparent that products of combustion from the burners 16 below the griddle 17 may pass through the opening 29 into the member 30, 110 and that the products of combustion rising into the flues 24, 26 and 21 of the oven may

pass through the opening 28 into the member 30.

As shown in the drawings, the solid fuel and gas heaters are located at the left side of the oven, but it will be apparent that the construction may be reversed with the solid fuel and gas heaters at the right side of the oven, so that said fuel and gas heaters may be located at either side or the back of the oven. The solid fuel and gas heaters are located between the partition 19 and the corresponding end or side wall 31 of the body 10. A horizontal partition 32 is disposed between the partition 19 and wall 31 above the body and extends forwardly from the back wall of the body, and a vertical partition 33 extends upwardly from the forward end of the partition 32. The forward end of the partition 32 and the partition 33 are spaced rearwardly from the front wall of the body, and said partitions 32 and 33 separate the solid fuel and gas heaters. A shaking or other suitable bottom grate 34 is located above the partition 32 between the partition 33 and back wall of the body, and the space 35 between the grate 34 and partition 32 provides an ash pit in which an ash pan (not shown) may be disposed as usual for catching the ashes that pass down through the grate 34. The wall 31 of the body has an ash door 36, which, as shown, is hinged to swing downwardly, in order that the ashes may be readily removed. As shown, the grate 34 has a stem or shank 37 projecting out through the wall 31 above the door 36 in order that the grate may be vibrated to shake down the ashes. Above the grate 34 is the firebox 38 in which coal, wood, coke or other solid fuel may be burned, and said firebox may be lined as usual. The top of the body has the removable lids 39 above the firebox, and the back wall of the body has the outlet opening 40 for the discharge of the products of combustion from the firebox into the pipe or flue attaching member 41 to which the stove pipe or flue is connected as usual. A damper 42 is mounted in the member 41 to check the draft when desired. As seen in Fig. 2, a forwardly inclined partition 43 extends from the upper end of the partition 33 and front end of the firebox 38 to the upper edge of the front wall of the body above the space between said front wall and partition 33. By this arrangement the upper portion of the firebox is extended forwardly to the front wall of the body, and it will be noted that the front lid 39 extends over the partition 43. The coal or other solid fuel is deposited in the firebox 38 by removing the lids 39, and any coal or solid fuel that is dropped down through the front opening will slide down the partition or plate 43 into the firebox, said partition 43 providing a chute to direct the fuel rearwardly into the firebox proper.

Coming to the gas heater, it is located in front of the solid fuel heater, in the space between the partition 33 and front wall of the body. The front wall of the body has a front plate 44 for the gas heater extending across the space between the front edges of the partition 19 and wall 31, and said front plate 44 has an opening or window 45 of suitable size between its upper and lower ends, with the edges of the plate surrounding said opening turned rearwardly, as seen in Figs. 2, 5 and 6.

The gas heater is of the radiant type, and includes the upright radiants 46 composed of suitable refractory material and having suitable openings for the outlet of the flames and products of combustion from said radiants. The radiants 46 are located behind the opening 45 and are exposed through said opening, and when heated will radiate heat outwardly or forwardly through the opening 45.

The lower ends of the radiants 46, which are open, are seated on a shelf or horizontal plate 47 disposed in rear of the lower edge of the opening 45, with the lower ends of the radiants disposed over a battery of Bunsen burner tubes 48. As shown, the tubes 48 are integral with the shelf 47 and a horizontal bar 49 below the shelf 47, said tubes 48 being cast in one unit. The ends of the bar 49 have depending collars 50 receiving a horizontal gas pipe 51 that extends through the flue 27 below the oven bottom 15. The pipe 51 may be secured in the collar 50 by means of set screws or the like. The pipe 51 has upwardly extending discharge nipples 52 projecting upwardly into the tubes 48 to discharge the gas upwardly into said tubes, and the lower ends of the tubes are open so as to admit air to mix with the gas. The gas discharges upwardly from the tubes 48 into the radiants 46, and screens 53 or other diffusers are disposed across the upper ends of the tubes 48. The radiants 46 are disposed side by side between the partition 19 and wall 31, and their front walls are of lattice construction to provide forwardly directed openings through which the flames and heat may pass. The pipe 51 is connected by a control valve 54 with a branch 55 of the gas supply pipe 18, and the wall 31 carries a cap plate 56 to receive and enclose the end of the pipe 51 which protrudes through the wall 31, as seen in Fig. 4.

An upright back plate 57 for the radiants 46 is provided, said radiants being disposed in front of said plate, and said plate being spaced in front of the partition 33. The plate 57 is secured to the partition 33 by means of bolts 58 or other securing elements, with spacers 59 between said plate and partition to space them apart. The plate 57 has forwardly extending ears 61 at its lower edge on which the shelf 47 is secured by means of bolts or other securing elements, thereby sup-

porting the shelf 47 from the plate 57 which is in turn supported from the partition 33. The plate 57 has its front surface formed with vertical corrugations, so that said plate 57 assists in reflecting the heat forwardly from behind the radiants, and said plate has horizontal forwardly extending ribs 60 against which the radiants 46 bear, thereby spacing said radiants slightly from the plate 57, with a clearance between them for the flow of air and products of combustion upwardly between the radiants and plate 57.

10 A deflecting plate 62 is disposed behind the upper portion of the opening 45, and is loosely connected at its upper edge with the front plate 44 at the upper edge of the opening 45 by means of a bolt 63 or other securing element. Said plate 63 extends downwardly and rearwardly at an angle from the upper edge of the opening 45 with its lower edge extending across the radiants near the upper ends thereof, thereby holding the radiants against the back plate 57. Furthermore, air rising from the radiants will be deflected forwardly into the room by the plate 62, so that said plate serves the double function of holding the radiants in place and deflecting the heated air forwardly. A sill plate 64 is disposed across the lower edge 20 of the opening 45 and its rear edge extends across the radiants 46 at the lower ends thereof, to hold said radiants on the shelf 47. Said plate 64 also provides a neat finish for the lower end of the opening 45. The plate 30 64 has projecting end portions 65 to engage behind the front plate 44. Upright corner pieces 66 are secured in the corners between the front plate 44 and partition 19 and wall 31, and the portions 65 engage behind the corner pieces 66, as seen in Fig. 5. This will 40 hold the plate 64 in place, and one piece 66 has a lug 67 to project over the corresponding portion 65 so as to hold the plate 64 down. In order to remove said plate it is necessary to swing the opposite end of the plate upwardly so as to withdraw the plate from under the lug 67 and outwardly through the opening 45. When the plate 64 is removed the radiants 46 may be raised 50 slightly so as to lift them off the shelf 47 and tubes 48 and the radiants may then be removed by swinging their lower ends forwardly and then withdrawing the upper ends of the radiants from between the plates 57 and 62. This enables the radiants to be taken out for cleaning, repair or replacement.

A rearwardly extending baffle 68 is secured to the front plate 44 below the gas burners 60 of the gas heater, and the front plate 44 has air inlet apertures 69 in front of the gas burner between the plate 64 and baffle. Said front 44 also has air outlet apertures 70 above the opening 45 or between the plates 65 43 and 62. The apertures 69 and 70 near

the lower and upper ends, respectively, of the plate 44 are for the admission and discharge of air flowing to and from the gas heater. The chamber or flue 71 below the partition 32 is open at the bottom in rear of 70 the baffle 68, so that air may flow upwardly into said chamber or flue 71 and thence upwardly through the flue or space 72 between the partition 33 and plate 57, so as to be heated by contact with the plate 57. From 75 the flue 72 the heated air rises into the space 73 above the radiants between the plate 62 and partition 33 and below the plate 43, and the heated air passes forwardly through the openings 70 into the room. It will also be 80 noted that when the solid fuel heater is used, air passing upwardly through the flue 72 and space 73 will be heated by the partition 33 and plate 43, thereby providing for the circulation of air in the room when heated by 85 either solid fuel or gas.

The partition 19 has an opening 74 establishing communication between the space 73 above the radiants 46 and the flue 21. Thus, products of combustion rising from the radiants or gas burner into the space 73 may be drawn off through the flue 21, thus preventing at least some of the products of combustion from passing into the room. If desired, the opening 74 may be in the partition 33 so 90 that the products of combustion are discharged into the firebox to be drawn off with the products of combustion of the solid fuel. The gas fumes are thus drawn off by the usual draft provisions of the range or 100 stove.

The present structure provides for a three-way combination, namely, (1) a gas range with a cooking top and a baking oven, (2) a heater using coal or other solid fuel, and 105 (3) a radiant gas heater. Thus, either solid fuel or gas may be used for heating, or, if desired, both heaters may be used simultaneously, although this may not ordinarily be necessary. The gas heater occupies the space 110 in front of the solid fuel heater, within the outline of the body 10, with an extension of the firebox overhanging the gas heater, it being noted that the plate or partition 43 serves as a chute for the solid fuel delivered 115 into the firebox, and also serves to deflect heated air rising in the space 73 forwardly through the openings 70. The air rising 120 through the flue or space 72 will be heated from either the solid fuel or gas heater. When the radiant gas heater is used, heat is radiated outwardly or forwardly through the opening or window 45 directly into the room, and air also flows upwardly behind the back plate 57 of the radiants through 125 the flue or space 72 so as to provide for a circulation of air in the room.

Having thus described the invention, what is claimed as new is:

1. A cooking range having a solid fuel 130

- heater with a firebox, and a built-in radiant gas heater, said firebox having an inclined portion overhanging said gas heater for deflecting fuel from above into the firebox and for deflecting air from below outwardly.
2. A cooking range comprising a body having an opening in one wall thereof, a solid fuel heater in the body including a vertical partition spaced from said wall, and a radiant gas heater disposed between said partition and wall and exposed through said opening, said solid fuel heater having a firebox provided with an inclined portion overhanging the gas heater and extending to said wall.
3. A range comprising a body having an opening in one wall thereof, a plate mounted in the body adjacent to said opening, radiants bearing against said plate and exposed through said opening, gas burners below the radiants, and plates mounted in the upper and lower portions of said openings and removably connected with the body, said plates extending across said radiants to hold them in place against the firstnamed plate.
4. A range comprising a body having an opening in one wall thereof, a vertical partition within the body, a plate secured to and spaced from said partition, gas burners including a shelf secured to and supported from said plate, and radiants seated on said shelf over the burners and bearing against said plate.
5. A range comprising a body having an opening in one wall thereof, a vertical partition within the body, a plate secured to and spaced from said partition, gas burners including a shelf secured to and supported from said plate, radiants seated on said shelf over the burners and bearing against said plate, and plates mounted in the upper and lower portions of said opening and extending across upper and lower portions of the radiants to hold them against the firstnamed plate.
6. A range comprising a body having an opening in one wall thereof, a shelf mounted in the body, radiants seated on said shelf, gas burners below the radiants, and a sill plate disposed across the lower portion of the opening and extending across the lower portions of the radiants to hold them in place on said shelf.
7. A range comprising a body having an opening in one wall thereof, a plate mounted in the body adjacent to said opening, radiants bearing against said plate and exposed through said opening, a shelf mounted in the body and on which the radiants are seated, gas burners below the radiants, and a sill plate extending across the lower portion of said opening and across the lower portions of the radiants to hold the radiants in place on the shelf against the firstnamed plate, said sill plate having portions to engage behind said wall to hold said sill plate in place.
8. A cooking range comprising a body, having an opening in one wall thereof, a solid fuel heater within the body including a vertical partition adjacent to said opening and an inclined portion extending from said partition to said wall above said opening, said wall having air outlet apertures between said portion and opening, a heat reflecting plate between said partition and opening, radiants disposed in front of said plate and exposed through said opening, gas burners below said radiants, and plates within the upper and lower portions of said opening and extending to the radiants.
9. A range comprising a body having an opening in one wall thereof, a solid fuel heater within the body including a partition spaced from said opening and adapted to be heated by said heater, a radiant gas heater between said partition and opening and exposed through said opening, with a vertical air passage between said partition and gas heater so that the air in said passage is heated by said partition and gas heater.
10. A range comprising a body, a radiant gas heater in the body, and a solid fuel heater in said body, said heaters being spaced apart and having a vertical air passage between them so that the air in said passage is heated from either heater.
11. A range comprising a body having an opening in one wall thereof, a solid fuel heater in the body having a partition spaced from said opening and adapted to be heated by said heater, a plate between said partition and opening and spaced from said partition to provide a vertical air passage in which the air is heated from either said partition or plate, and a radiant gas heater in front of said plate exposed through said opening.
12. A cooking range having a body and a heater therein with a space between said heater and one wall of the body and a closed partition separating said heater and space from one another and capable of being heated from said heater, said wall having an opening, and a built-in radiant gas heater within said space and exposed through said opening, said partition and gas heater being spaced apart for the flow of air between them and each being capable of heating the air between them.
13. A cooking range having a body and a heater therein with a space between said heater and one wall of the body and a closed partition separating said heater and space from one another and capable of being heated by said heater, said wall having an opening, a built-in radiant gas heater within said space and exposed through said opening, and provisions for the flow of air upwardly between said partition and gas heater.

- er from a point below to a point above said gas heater, and said partition and gas heater each being capable of heating the air which flows upwardly between them.
- 5 14. A cooking range having a body and a heater therein with a space between said heater and one wall of the body and a closed partition separating said heater and space from one another and capable of being heated by said heater, said wall having an opening, a built-in radiant gas heater within said space and exposed through said opening, and a plate between said gas heater and partition and adapted to be heated by said 10 gas heater, said partition and plate being spaced apart to provide an air passage for the upward flow of air between said heaters and said plate and partition each being capable of heating the air flowing in said 15 passage.
- 20 15. A cooking range having a body and a heater and oven therein disposed side by side, with a flue surrounding the oven and a space between said heater and one wall of the body and a closed partition separating said heater and space from one another and capable of being heated by said heater, said 25 wall having an opening, and a built-in radiant gas heater within said space and exposed through said opening, said flue having an opening above said gas heater for drawing off products of combustion therefrom, and said partition and gas heater being spaced apart and each being capable of heating 30 the air in the space between them.
- 35 16. A cooking range comprising a body, a solid fuel heater in the body including an interior vertical partition spaced inwardly from one wall of the body and separating 40 said heater from the space between said partition and wall, said partition being capable of being heated by said heater, said wall having an opening, and a radiant gas heater disposed in said space and exposed through said opening, said gas heater being spaced 45 from said partition to provide an air passage between them and said gas heater and partition each being capable of heating the air in said passage.
- 50 17. A cooking range having a body and a heater therein with a space between said heater and one wall of the body and a closed partition separating said heater and space from one another and capable of being heated by said heater, said wall having an 55 opening, and also having air inlet and outlet apertures below and above said opening, respectively, a built-in radiant gas heater within said space and exposed through said opening, and provisions for the upward passage of air behind said gas heater from the air inlet apertures to the air outlet apertures, said partition and gas heater each being capable of heating the air which flows 60 behind said gas heater.
- 65 18. A cooking range comprising a body and a heater therein with a space between said heater and one wall of the body and a closed partition separating said heater and space from one another and capable of being heated by said heater, said wall having an opening and air inlet and outlet apertures below and above said opening, respectively, a radiant gas heater in said space and exposed through said opening, and a 70 plate between said gas heater and partition adapted to be heated by said gas heater, said partition and plate being spaced apart to provide a vertical air passage between them communicating with said air inlet and outlet apertures, and said partition and plate each being capable of heating the air flowing 75 in said passage.
- 80 In testimony whereof I hereunto affix my signature.
- HENRY LANGE.
